ABSTRACT: A stacking machine in which a stacking conveyor is pivotable about a horizontal axis to vertically adjust the height of the discharge end of the conveyor with respect to a stack of sheets being discharged from the conveyor with a cam connection connecting the means for adjusting the height of the conveyor to a platform support for the stack to consequently position the stack immediately beneath the discharge end of the conveyor in order that the stack will be beneath the discharge end of the conveyor regardless of the height of the discharge end of the conveyor and all sheets will be deposited in vertical alignment.

SHEET STACKER WITH STACK SUPPORT POSITIONER**BACKGROUND OF THE INVENTION**

This invention is in the field of sheet feeding and stacking means and is particularly directed to a stacking machine in which the position of the stack is adjusted in accordance with the position of the discharge conveyor feeding sheets to the stack.

Many prior known devices have evolved for the purpose of enabling the feeding of corrugated sheets or the like to a stack. For example, the device shown in German Pat. No. 1,204,145 includes a pivotable conveyor that is pivotable about a horizontal axis adjacent its inlet end for adjusting the height of the discharge end of the conveyor in accordance with the height of the stack to which the sheets are being fed. This conveyor is provided with means for extending or retracting the discharge end of the conveyor to vary the length of the conveyor in order that the discharge end of the conveyor will always be in a common vertical plane regardless of the angle of orientation of the conveyor. Otherwise, the discharge end of the conveyor would move in an arcuate path of travel and sheets discharged from the conveyor would not be deposited in a vertical array.

Other prior known sheet stackers such as that shown in British Pat. No. 775,937 have included a dual conveyor elevator system for insuring that the deposited stack of sheets is oriented in vertical alignment.

The present invention represents a vast improvement over the prior known devices for the purpose of stacking sheets in that it enables the use of a simple pivotable conveyor in which there is no need for providing means for adjusting the length of the conveyor in the manner of the aforementioned German patent or for providing dual conveyor elevator means in the manner of the aforementioned British patent.

SUMMARY OF THE INVENTION

Therefore, it is the primary object of this invention to provide a new and improved sheet stacker.

Obtainment of the object of this invention is enabled through the provision of a fixed-length stacking conveyor that is pivotable about a horizontal axis adjacent its infeed end for adjusting the height of its discharge end. Rotary means is provided for adjusting the height of the conveyor and a cam and lever connection is connected between the rotary means and a movable carriage upon which the sheets are stacked. The dimensions of the connections are such that the carriage is moved in exact accordance with the position of the discharge end of the conveyor so that the sheets are consequently deposited in an exact vertical alignment on the carriage.

DESCRIPTION OF THE DRAWINGS

FIG. 1 is a side elevational view of the preferred embodiment of this invention; and

FIG. 2 is a plan view of the preferred embodiment illustrated in FIG. 1.

DESCRIPTION OF THE PREFERRED EMBODIMENT

The preferred embodiment of this invention includes first and second frame plates 1 that are connected by transversely extending braces 2, 3 and 4 of substantial dimensions and are also connected by a number of horizontal shafts or rods to be discussed hereinafter. In any event, wheels 5 and 6 are mounted on axles 7 and 8 extending between the two frame plates 1 to provide a movable carriage construction for supporting control and drive means to be discussed.

A pivot shaft 9 extends between frame elements 1 as shown in FIG. 1 and provides a pivotable support for a pivotable sheet stacking conveyor designated 10. Conveyor 10 is of conventional design and is formed with a pair of longitudinal side braces 13 which are pivoted on their right end as viewed in FIG. 1 to the pivot shaft 9. Conveyor 10 is of conventional belt-type construction in which a plurality of driven feedbelts

10' (the number depending upon the width of the conveyor) are mounted on and extend between a downstream roller 12' and an upstream roller 9' respectively mounted adjacent the outfeed and infeed ends of the conveyor. The roller 9' is mounted on shaft 9 which is driven by means to be discussed hereinafter in order that the upper flight of the conveyor will move from right to left in FIG. 1 in the direction indicated by the arrow F'.

Sheets to be stacked are fed to the infeed end of conveyor 10 by means of a belt-type conveyor 14 which is trained over pulleys on axle 9 and is also trained over idler pulleys 15 mounted from a shaft extending between frame plates 1. The infeed conveyor 14 can be of any conventional type and any type conveyor that would feed sheets to the conveyor 10 would be satisfactory for this purpose.

A pair of stub shafts 16 extend inwardly from plates 1 in aligned relationship with respect to each other for providing rotary support for a pair of positioning wheels 17 mounted on shafts 16 for rotation. Positioning wheels 17 are chain driven for rotary adjustment in a manner described hereinafter.

Additionally, a pair of running wheels 18 are provided on stub shafts 18' extending inwardly from the inside surfaces of the positioning wheels 17. It should be noted that the running wheels 18 are mounted eccentrically with respect to the axis of rotation of positioning wheels 17 so that rotation of positioning wheels 17 will cause the axis of running wheels 18 to traverse the path P illustrated in FIG. 1 of the drawings.

Additionally, cams 19 which are coaxial with the axis of shafts 16 are mounted on shafts 16 adjacent the wheels 17 for rotation therewith. A pair of pivot levers 20 are mounted on pivots 22 extending inwardly from the inner surface of the frame plate 1. Pivot levers 20 are provided with cam follower rollers 21 mounted for rotation intermediate their ends for engagement with the cams 19. The lower ends of the pivot lever 20 are pivotally connected by pivot bearings 24 to drawbars 25 which are in turn connected to coupling bolts 26 of a stack receiving carriage 45 mounted for reciprocation on wheels 46 in an obvious manner. Carriage 45 also includes a plurality of rollers 48 for supporting sheets deposited on the carriage.

Belts can be provided over the rollers 48 if desired. Additionally, a coil spring 36 is engageable with a fixed foot plate 37 on one end a large washer 36' on the right end of a bias rod 69. Bias rod 69 extends through an aperture in the foot plate 37 and has its left end pivotally connected to the lower end of pivot lever 20 as shown in FIG. 1. Consequently, the biassing force of compression spring 36 serves to pivot lever 20 in a counterclockwise direction about axis 22 so that the cam follower rollers 21 engage their respective cams 19. Moreover, it will be obvious that the pivotal movement of the lever 20 serves to reciprocate the carriage 45 in an obvious manner.

Drive to wheels 17 is provided by a combination motor and gear reducing unit 28 which drives gear wheels 31 keyed to a main drive shaft 30. The main drive shaft 30 is mounted for rotation in bearings 29 and has an output drive sprocket 33 attached to each end and from which a drive chain 35 extends in connection with an intermediate sprocket 35' which serves to drive an output sprocket 32. A chain 34 extends from sprocket 32 in driving connection with the wheels 17 so that rotative power from the motor unit 28 serves to rotate wheels 17. Motor 28 etc. is mounted on a base plate 27.

Therefore, it will be seen that rotation of wheels 17 caused by actuation of motor 28 will serve the dual purpose of positioning the conveyor 10 at a desired angle while simultaneously serving to position the carriage 45. The dimensions of lever 20 etc. are such that the discharge end 12 of the conveyor 10 always remains in vertical alignment with a particular given point on carriage 45. Consequently, sheets discharged from the discharge end are always deposited in exact vertical alignment with respect to each other regardless of the angle at which the conveyor 10 is oriented at the time of discharge of the respective sheets. It should be noted that the conveyor 10 is capable of movement

70

75

70

75

downwardly from the uppermost position illustrated in FIG. 1 through an intermediate dotted line position to a lower position which is also illustrated with dotted lines. Moreover, reverse rotation of the wheels 17 will serve to pivot the conveyor 10 in a clockwise direction A while rotation of the motor 28 in the opposite direction will pivot the conveyor in a counterclockwise direction B as shown.

Additionally, a control bar having an axis 41 is pivotally connected to the frame 1 at 40 on each side of the conveyor 10. The upper ends of the rods having axis 41 are connected to a support 42 of a stacking guide 43. Lateral displacement of the stacking guide 43 either to the right or left in FIG. 1 is enabled by an adjustment wheel 44 in an obvious manner. Moreover, it should be noted that the parallelogram relationship between axis 41, conveyor 10, support 42 and the protrusion of frame 1 upon which connection 40 is made always results in a vertical orientation of the stacking guide 43. Consequently, sheets conveyed by the conveyor 10 will engage guide 43 prior to deposit in vertical alignment on the carriage 45. Guide 43 always remains above a given point on carriage 45 so that the sheets are deposited in exact vertical array.

Conveyor 10 rests by its own weight on the running wheels 18 so that rotation of the wheels 17 which support the running wheels 18 serves to angularly position conveyor 10. Motor 28 is driven at a speed in accordance with the driving speed of conveyor 10 so that the discharge end of conveyor 10 will move upwardly as the height of a stack of sheets on carriage 45 progresses upwardly. Consequently, all of the sheets will be deposited in aligned array.

Drive for the conveyors 14, 10 is provided by a motor-speed reducer unit 38 which is drivingly connected to shaft 9 by a chain 39 in an obvious manner as shown in (FIG. 1).

I claim:

1. Stacking means comprising frame means, a horizontally extending pivot shaft attached to said frame means, an elong-

gated driven belt conveyor pivotally connected on its infeed end to said pivot means, power driven conveyor adjusting means for adjustably positioning said conveyor about said pivot means for adjusting the vertical height of the downstream end of said conveyor, movable stack supporting means located beneath the downstream end of said conveyor for receiving sheets fed from said conveyor and linkage control means connected between said power driven conveyor adjusting means and said movable stack supporting means for 5 adjusting the position of said movable stack supporting means for maintaining corresponding portions of the downstream end of said conveyor and said stack supporting means in vertical alignment for all vertical positions of the downstream end of said conveyor.

15 2. The invention of claim 1 wherein said power driven conveyor adjusting means includes rotary positioning wheels having eccentric running wheels engageable with the lower side of said conveyor whereby the rotary position of said wheels determines the vertical height of the downstream end of said conveyor.

20 3. The invention of claim 2 wherein said linkage control means connecting said stack supporting means to said power driven conveyor adjusting means includes a cam member fixedly connected to said positioning wheels for rotation therewith, a pivot lever having a cam follower intermediate the ends of said pivot lever and engageable with said cam means so as to be moved in timed relationship to said power driven means for adjustably positioning said conveyor and a bias rod connecting said carriage to said pivot lever.

25 30 4. The invention of claim 3 additionally including a stacking guide pivotally connected to the downstream end of said conveyor and a control bar connected to said stacking guide and said frame for maintaining said stacking guide in vertical orientation regardless of the orientation of said conveyor.
